UNITED STATES PATENT OFFICE.

FRANK A. GOODYKOONTZ, OF MIAMI, ARIZONA.

SCRAPER FOR BELTS.

1,299,324.

Specification of Letters Patent.

Patented Apr. 1, 1919.

Application filed April 12, 1918. Serial No. 228,232.

To all whom it may concern:

Be it known that I, FRANK A. Goodykoontz, a citizen of the United States, residing at Miami, in the county of Gila and 5 State of Arizona, have invented new and useful Improvements in Scrapers for Belts, of which the following is a specification.

In endless conveyers employed in handling plastic material, such materials necessarily 10 stick to the belt, and unless such substances are removed the conveyer is rendered defective. A direct scraping of the conveyer belt will wear down the same, thus shortening the life thereof, while any hardened member directly contacting with the belt, even intermittently, will inflict injury to the belt.

It is the primary object of this invention to provide a means for removing foreign substances from an endless belt conveyer which 20 will deliver intermittent blows to the belt and intermittently scrape the belt, the construction and arrangement of the same being such, however, as to inflict no injury to the belt.

In carrying out my invention I propose to 25 provide a shaft or drum with radial arms having on the ends thereof strips of yieldable material, the shaft or drum being latched to the motive power which produces the conveyer and being so arranged as to deliver 30 light blows to the conveyer, upon the bottom lead thereof as well as to impart scraping action to the said lead, and thereby automatically relieve the belt of substances or particles adhering thereto.

35 I accomplish the foregoing objects and others which will appear as the nature of the invention is better understood, by a simple construction, combination and arrangement of parts, a satisfactory embodiment of which 40 is illustrated by the drawings, in which,

Figure 1 is an edge view of an endless conveyer illustrating the application of the improvement.

Fig. 2 is a greatly enlarged sectional view 45 approximately on the line 2—2 of Fig. 1.

Fig. 3 is a perspective view of the scraper, the flexible belt in contact therewith being removed.

Fig. 4 is a perspective view of one of the 50 belt contact members.

Fig. 5 is a view of the shaft for the improvement.

Fig. 6 is a detail sectional view illustrating the manner in which the drums are secured 55 on the shaft.

Referring now to the drawings in detail

6 designates an endless conveyer belt and 7 one of the pulleys around which the belt travels. The pulley 7 may have its shaft 8 connected to the source of power for operating the belt, but for the purpose of this invention it has not been deemed necessary to illustrate the motive power.

While in the drawings I have illustrated the improvement as deriving power from an 65 idler 9 that is contacted and revolved by the lower lead of the conveyer belt 6, it will, of course, be apparent that the improvement may be hitched directly to the shaft 8, or to the shaft of any of the rollers for the belt 6. 70

Journaled in suitable bearings provided in uprights 10 arranged to the opposite sides of the conveyer belt 6, and preferably positioned a slight distance inward of the axial center of the roller 7, is a shaft 11. This 75 shaft is provided with spaced keyways 12 within which are arranged keys 13 that also pass through keyways 14 in wheels or drums 15, any desired number of the latter being employed, and the same being preferably 80 spaced away from each other. As disclosed by the drawings the drums 15 are preferably in the nature of flat disks and are each provided with a desired number of equally spaced arms 16 which radiate from the drums 85 15. The arms 16, at the outer ends thereof are bent upon themselves to provide angularly disposed flat flanges 17. Secured to the flanges are metal plates 18, and secured to the said plates 18 are the scraper plates 19. 90

The plates 19 are constructed each of a strip of yieldable material, such as rubber, the same having their outer edges projecting a suitable distance beyond the outer edges of the plates 18, and the scraper plates 19 are 95 preferably adjustably connected to the plates 18. This is accomplished by providing the plates 18 with elongated openings 20 which register with the openings in the plates 19 through which the securing elements pass, 100 but if desired, a plurality of elongated openings may be arranged on the scraper plates.

The scraper plates are disposed to contact with the under lead of the belt 6, as clearly disclosed in Figs. 1 and 2 of the drawings, 105 so that both a shaking and a scraping action will be imparted to the lower lead of the belt when the device is operated.

On the shaft 11 is secured a pulley 21 around which is trained a twisted belt 22, 110 the said belt being also trained around the idler 9. It will be apparent that when the

belt is in operation and moves in the direction of the arrows illustrated in Fig. 1 of the drawings the idler 9 will be turned in the direction of the arrow shown on the said figure, revolving the scraper members in an outward direction, or in a direction opposite to that of the movement of the belt 6.

The device is extremely simple, may be easily and cheaply set up in connection with 10 any ordinary construction of conveyer belts and will, as stated, impart both a striking and scraping action to the belt, consequently effectively removing all foreign incrustations, dirt and dust therefrom.

15 Having thus described the invention, what I claim is:

1. In combination with an endless belt, a shaft arranged therebeneath and operated thereby, drums on said shaft, radial arms 20 projecting from said drums having flat flanged ends, plates secured to said ends, and

elastic scraper plates adjustably connected to said last mentioned plates and disposed to contact with the belt.

2. In combination with an endless belt, a 25 shaft arranged therebeneath and operated thereby, equi-distantly spaced drums removably secured on the shaft, each of said drums having a plurality of radially disposed arms the outer ends of which are bent upon themselves to provide angularly disposed flat flanges, metallic plates secured on the said flanges, elastic scraper plates adjustably secured on the metallic plates, and securing elements between the elastic and the metallic 30 plates certain of which elements connect both plates to the flanges of the arms, said elastic scraper plates disposed to contact with the belt.

In testimony whereof I affix my signature. 40

FRANK A. GOODYKOONTZ.
